ROLLING MILL GUIDE

Joseph M. O'Malley, Worcester, Mass., assignor to
 Morgan Construction Company, Worcester,
 Mass., a corporation of Massachusetts

Application January 8, 1940, Serial No. 312,856

3 Claims. (Cl. 80—51)

This invention relates to rolling mill guides, and more particularly to entrance guides of the type having means for opening and closing the same.

In certain rolling operations it is necessary to grasp the front end of a hot metal bar by means of a pair of tongs, as it issues from one stand of rolls, and insert this front end in a succeeding roll stand. This may be difficult to accomplish if the entrance guide fits the bar tightly, and yet a tight guide is desirable in order to maintain the proper control of the bar. For this reason it has been proposed to utilize two complementary guide blocks, one of which is fixed and the other of which is movable laterally, the movable block being held against the bar by a manually actuated wedge or screw. With this construction it is possible to loosen the movable block until the front end of the bar has been inserted between the rolls, and then to tighten the block so that it will fit closely against the bar. With such guides, however, the opening movement is unsymmetrical so that the bar in entering the mill must rub against the stationary guide block. This adds to the difficulty of inserting the bar. Moreover, the guide will not open of its own accord, even after the wedge or screw is loosened, and the bar itself is depended upon to force the movable block to one side. There is serious danger of bending or upsetting a hot bar during this procedure.

It is accordingly one object of the invention to provide a rolling mill guide which will open in a symmetrical manner with respect to a plane extending through the pass line of the mill.

It is a further object of the invention to provide a guide which will be self-opening upon manual release of the actuating mechanism.

It is a further object of the invention to provide a guide which is simple and inexpensive to manufacture, and thoroughly dependable in operation.

With these and other objects in view, as will be apparent to those skilled in the art, the invention resides in the combination of parts set forth in the specification and covered by the claims appended hereto.

Referring to the drawing illustrating one embodiment of the invention and in which like reference numerals indicate like parts,

Fig. 1 is a side view of a rolling mill entrance guide, shown in section on the line 1—1 of Fig. 4;

Fig. 2 is a section on the line 2—2 of Fig. 1, the guide being in its closed position;

Fig. 3 is a view similar to Fig. 2 but showing the guide in its open position;

Fig. 4 is an elevation taken in the direction of the arrow 4 in Fig. 1; and

Fig. 5 is a section on the line 5—5 of Fig. 2.

The embodiment illustrated comprises a pair of spaced upright housings 10, and two horizontal rolls 11, these parts being of the usual construction employed in the rolling of metal bars. A horizontal rest bar 12 extends between the housings at the front or entrance side of the rolls. 10 On this rest bar there is mounted a guide box 14 within which two complementary guide blocks 15 are located. The blocks 15 are formed on their adjacent faces with grooves 16 suitably shaped to fit the cross-section of the bar which is to pass therethrough. Flanges 18 are provided on the front ends of the guide blocks, these flanges engaging the front of the box 14 to prevent the blocks from moving in the direction of stock travel. 15 20 The guide blocks 15 rest on the bottom of the box 14, and the center of gravity of each block is located outside the supported area of the block, so that the blocks tend to tip laterally away from one another by reason of their own weight. This 25 is brought about by cutting away the lower outside corners of the blocks, as indicated at 19, in such a manner that only a comparatively narrow area of each block is in contact with the bottom of the guide box, this area being located close to 30 the vertical plane which extends through the pass line of the rolling mill. Two wedges 20 are provided on opposite sides of the blocks 15 so that they may be forced together to afford the desired close fit against the bar after the front end 35 thereof has been gripped by the rolls 11. The wedges 20 are vertically slidable in grooves 22 formed in the upright side walls of the guide box 14. As shown particularly in Fig. 2, when the 40 blocks 15 are inclined at the same angle as the inner surfaces of the wedges 20, so that the blocks will be firmly supported by the wedges against the lateral pressure of the stock.

Means is provided to move the wedges 20 up 45 and down in the grooves 22. For this purpose each wedge is provided with a lug 24 on its upper end, these lugs being located on opposite sides of the rear end of a lever 25 and connected thereto by a pin 26. The lever 25 is fulcrumed 50 on a pin 28 which is supported in a pair of spaced ears 29 projecting upwardly from the guide box 14. Two adjustable screws 30 and 31 extend through the lever 25 respectively in the rear of and in front of the fulcrum pin, in position to 55 engage the guide box and thus limit the move-

ment of the lever in each direction. The front end of the lever is connected by means of upright links 33 to a short arm 34 which projects rearwardly from a hub 35. This hub is keyed to a transverse horizontal shaft 37 which is rotatably supported in two bearings 38 mounted on the front of the housings 10. An arm or handle 39 is secured to one end of the shaft 37 and projects forwardly therefrom in a position for convenient manual operation. It will be noted that the weight of the handle 39 tends to lift the front end of the lever 25 and thus lower the wedges 20 and force the guide blocks 15 together.

The operation of the invention will now be apparent from the above disclosure. When the front end of the bar is to be inserted in the mill, the operator will lift the handle 39; thus turning the shaft 37 and raising both the wedges 20 simultaneously. The guide blocks 15 will thereupon tip outwardly by their own weight, as shown in Fig. 3, and the bar can be readily shoved through the guide. As soon as the bar has been gripped by the rolls 11, the operator will lower the handle 39, which will move the wedges 20 downwardly and force the guide blocks 15 together, as shown in Fig. 2, so that the bar will be properly supported and guided. The extent of closing of the guide may be regulated by adjustment of the screw 30, whereas the extent of opening may be regulated by adjustment of the screw 31. Since both the guide blocks move away from the pass line, when the wedges are raised, the bar can be inserted in the roll grooves free from any tendency toward lateral crowding by the guide. Furthermore, the bar itself is not used to force the guide blocks apart, and there is little danger of buckling the bar. When the guide blocks require replacement they can be easily withdrawn from the front of the guide box. The construction is simple, inexpensive and dependable.

Having thus described my invention, what I

claim as new and desire to secure by Letters Patent is:

1. A rolling mill guide comprising two complementary guide blocks adapted to engage a bar of stock on opposite sides as it travels longitudinally along the substantially horizontal pass line of a rolling mill, means supporting the blocks from beneath the same, the center of gravity of each block being located outside the supported area of the block so that the blocks tend to tip laterally away from one another by reason of their own weight, and adjustable means to urge both blocks toward the pass line.

15 2. A rolling mill guide comprising two complementary guide blocks adapted to engage a bar of stock on opposite sides as it travels longitudinally along the substantially horizontal pass line of a rolling mill, means supporting the blocks from beneath the same, the center of gravity of each block being located outside the supported area of the block so that the blocks tend to tip laterally away from one another by reason of their own weight, two wedges engaging the blocks respectively to limit their outward tipping, and means to adjust both wedges simultaneously.

20 3. A rolling mill guide comprising two complementary guide blocks adapted to engage a bar of stock on opposite sides as it travels longitudinally along the substantially horizontal pass line of a rolling mill, means supporting the blocks from beneath the same, the center of gravity of each block being located outside the supported area of the block so that the blocks tend to tip laterally away from one another by reason of their own weight, two wedges having opposed inner surfaces which engage the outer surfaces of the respective blocks to limit their outward tipping, the said inner surfaces of the wedges sloping downwardly and outwardly, and means to adjust both wedges simultaneously in a vertical direction.

JOSEPH M. O'MALLEY.
